UNITED STATES PATENT OFFICE

143,694

DESIGN FOR A COMBINED VEGETABLE CHOPPER, PEELER, AND SLICER

Myron J. Zimmer, Wood Dale, Ill., assignor to Ekeco Products Company, Chicago, Ill., a corporation of Illinois

Application June 8, 1945, Serial No. 119,964

Term of patent 14 years

(Cl. D89—1)

To all whom it may concern:

Be it known that I, Myron J. Zimmer, a citizen of the United States, residing at Wood Dale, in the county of Du Page and State of Illinois, have invented a new, original, and ornamental Design for a Combined Vegetable Chopper, Peeler, and Slicer, of which the following is a specification, reference being had to the accompanying drawing, forming part thereof.

Fig. 1 is a side view of the combined vegetable chopper, peeler, and slicer, showing my new design.

Fig. 2 is an end view thereof.

I claim:

The ornamental design for a combined vegetable chopper, peeler, and slicer, substantially as shown.

MYRON J. ZIMMER.
